ALKYLATION OF HYDROCARBONS

Ernest F. Pevere, Beacon, and Louis A. Clarke and George B. Hatch, Fishkill, N. Y., assignors to The Texas Company, New York, N. Y., a corporation of Delaware

Continuation of application Serial No. 221,918, July 29, 1938. This application May 17, 1945, Serial No. 594,216

17 Claims. (CL 260—683.4)

This invention relates to the alkylation of hydrocarbons and particularly to the alkylation of isoparaffins with olefins in the presence of a liquid catalyst for the production of gasoline and has to do more specifically with the regulation of the proportion of catalyst in the reaction mixture in a continuous process.

This is a continuation of our copending application Serial No. 221,918 filed July 29, 1938.

In the alkylation of isoparaffins with olefins in the presence of strong sulfuric acid, or similar catalyst, it is advantageous to obtain intimate contact between the catalyst and hydrocarbons. To this end it is customary to maintain as efficient agitation as possible. There are indications that the more efficient the agitation the smaller the acid dosage required. Perfect agitation is difficult to obtain, consequently it is desirable to compensate for lack of efficiency in, or to reinforce the effect of, the agitation. One method is to use a higher acid dosage in a premixed charge, but such means involve a large overall consumption of the acid and less efficient use thereof.

An object of the present invention is to obtain the benefits of a high acid dosage which is characteristic of the high ratio of acid to hydrocarbons in a premixed charge while retaining advantages of a low overall acid dosage.

Another object of the invention is to vary the rate of flow of the hydrocarbon relative to the rate of flow of the acid in the system, whereby a larger amount of hydrocarbon contacts a given amount of acid than is normally the case.

A further object of the invention is to variably control the ratio of acid to hydrocarbon in the reaction system to produce any desired acid dosage therein, independent of the ratio in the fresh feed.

The invention is not limited to any particular type of continuous system, but is particularly useful in a multiple stage operation using countercurrent or concurrent flow.

In accordance with the present invention, the ratio of acid to hydrocarbon in an individual reactor is preferably controlled by regulating the acid hold-up therein. In a continuous system, wherein the hydrocarbons and acid are continuously charged to a plurality of reactors, it is customary to use a certain ratio of acid to hydrocarbons, corresponding to predetermined ratios by weight of the acid to olefin. Normally the acid and hydrocarbon feed stocks pass through the reactors at a constant relative rate of flow. By creating an accumulation of acid in the reactors,

however, the rate of flow of the hydrocarbon may be substantially faster than the rate of flow of the acid, whereby a higher acid dosage or higher ratio of acid to hydrocarbon is obtained in a given reactor. This acid hold-up may be obtained by separating at least a portion of the acid from the mixture passing through the system and returning the acid to one or more reactors, or points in the system. By controlling the rate of recycling of the acid to the individual reactors, the amount of acid hold-up may be variably controlled. It has been found advantageous to obtain sufficient acid hold-up to increase the ratio of acid to hydrocarbon in the reactors to at least about two to five or more times that in the fresh feed.

The invention will be more fully understood from the following description read in connection with the accompanying drawings, in which Figure 1 is a diagrammatic sketch of suitable apparatus for carrying out the invention in connection with a countercurrent flow operation. Figure 2 is a modification showing the invention as applied to a concurrent type of operation. Figure 3 is a modification illustrating a means of creating acid hold-up in a mixer by regulating the acid level in the settler.

Referring to Figure 1, there is shown an apparatus for carrying out a five-stage countercurrent operation, each stage comprising a mixer equipped with suitable stirring mechanism and a settler. While five stages are shown, it is to be understood that any number of stages may be used. Isoparaffin charge, which may be any low boiling isoparaffin, such as isobutane, isopentane, isohexane or mixtures thereof, preferably isobutane, is drawn through the line 8 by the pump 6 and introduced into the mixer 7, wherein it is contacted with used acid from a previous settler, introduced through the line 8. The charge to the mixer 7 may be substantially only isoparaffin in which case it acts principally as a stripping agent for the used acid. The feature of stripping used alkylation acid with a substantially olefin-free low-boiling isoparaffin to remove absorbed olefin product from the acid and passing the isoparaffin with stripped olefin product to an alkylation reaction zone is disclosed and claimed in copending application, Serial No. 214,488, filed June 18, 1938, now Patent No. 2,256,450. Additional hydrocarbons, including recycle stock, referred to hereinafter, or a portion of the olefin charging stock, may also be introduced into the mixer through the lines 9 and 10 respectively. In the mixer, the hydrocarbons are intimately

contacted with the used acid and the mixture then transferred through the line 12 to a settler 14 wherein the hydrocarbons collect as a layer in the upper portion and the acid in the lower portion thereof. A constant level of acid may be maintained in the lower portion of the settler and the excess acid withdrawn through the valve controlled line 16 in which is located a pump 18 actuated by an automatic level control device 17. Any portion of the acid may be recycled from the settler 14 to the mixer 7 through the line 18 and pump 20 to maintain the desired acid hold-up in the mixer. The pump 20 may be controlled by a flow meter to recycle the desired amount of acid or a proportioning pump may be used instead of pumps 16 and 20.

Additional olefinic charging stock may be introduced through the line 22 into the hydrocarbon layer in the upper portion of settler 14. The feature of prediluting the olefin feed to an alkylation reaction zone with separated hydrocarbon phase or alkylate containing a high proportion of isoparaffins prior to contacting the olefin with the alkylation catalyst is disclosed and claimed in copending application, Serial No. 392,396, filed May 7, 1941, as a continuation-in-part of copending application, Serial No. 214,488, filed June 18, 1938. The resulting mixture is then transferred through the line 24 to a second mixer 25 wherein the hydrocarbons are intimately contacted with used acid introduced into the lower portion thereof, through the line 26. The mixture of hydrocarbon and acid is passed through the line 27 to the second settler 28 wherein the acid and hydrocarbon stratify. The used acid is withdrawn from the lower portion of the settler through the line 8, referred to heretofore, in which is located a pump 29 actuated by a constant level mechanism 30. Any portion of the used acid may be withdrawn from the lower portion of the settler through the line 32 and pump 33 and introduced into mixer 25 to create the desired acid hold-up therein. Olefinic charging stock may be introduced into the upper portion of the settler through the line 35 and the resulting hydrocarbon mixture transferred from the settler 28 through the line 36 to a third mixer 38. The hydrocarbons in the mixer 38 are intimately contacted with the used acid introduced into the lower portion thereof through the line 39. The acid and hydrocarbon mixture is transferred from the mixer 38 by the line 40 to a third settler 42. Acid and hydrocarbons separate in the settler, the acid being withdrawn from the lower portion thereof through the line 26, in which is located pump 44 actuated by a constant level mechanism 45. Acid is withdrawn from the bottom of the settler 42 through the line 47 and pump 48 to the mixer 38 to provide the desired acid hold-up in that mixer. Olefinic charging stock may be introduced into the upper portion of the settler 42 through the line 50.

The branch lines 10, 22, 35 and 50 communicate with an olefinic hydrocarbon charging line 52 in which is located a pump 53. By suitable regulation of the valves shown in the lines 10, 22, 35 and 50, the olefinic hydrocarbon charge may be split between any or all of the settlers 14, 28 and 42. The feature of splitting the olefin feed to an alkylation system, whereby the olefin is simultaneously introduced at a number of spaced points, is disclosed and claimed in copending application, Serial No. 213,148, filed June 11, 1938, now Patent No. 2,260,990. Also a portion or all of the olefinic charge may be intro-

duced into the mixer 7 through the line 10, but ordinarily it is preferable to make a multiple injection of the olefinic charge between only the settlers 14, 28, and 42. This olefinic charge may be any olefins which will alkylate the isoparaffins, such as normally gaseous olefins of more than two carbon atoms, or polymers thereof, including C₃ or C₄ fractions of cracked gases or mixtures thereof; propylene; butylene; isobutylene; polymer gasoline; disobutylene; or a butene-isobutene mixed polymer.

The hydrocarbon mixture in the top of settler 42 is passed through the line 55 to a fourth mixer 56 wherein it is contacted with acid introduced into the lower portion thereof through the line 58. The acid hydrocarbon mixture is conducted from the mixer 56 through the line 59 to a fourth settler 60. The acid separating in the settler 60 is passed through the line 69, referred to heretofore, to the mixer 38. Also acid is pumped from the lower portion of settler 60 through the line 62 to the mixer 56 to maintain the desired acid hold-up in the latter mixer. Hydrocarbons are passed from the upper portion of settler 60 through the line 64 to mixer 65 wherein the hydrocarbons are intimately contacted with fresh acid introduced into the lower portion thereof through the line 67 by the pump 68. This acid may be sulfuric acid around 92 to 98% strength and preferably about 94 to 96% concentration. The mixture of hydrocarbon and acid is conducted from the mixer 65 through the line 69 to a settler 70 in which the acid collecting in the lower portion thereof is withdrawn through the line 53 referred to heretofore. Any portion of this spent acid may be pumped through the line 72 to the mixer 65 to produce an acid hold-up therein.

The hydrocarbons are passed from the upper portion of settler 70 through the line 74 to a neutralizer or mixer 75 wherein the hydrocarbons are intimately contacted with an alkaline reagent, such as dilute caustic soda or soda ash solution, introduced through the line 77 and pump 78. The mixture of hydrocarbon and neutralizing agent is passed through the line 80 to a settler 81 wherein the neutralizing agent separates out as a layer in the lower portion thereof and may be recycled through the line 82 to the mixer 75 or withdrawn from the system through the valve controlled line 83.

The neutralized hydrocarbons are passed from the upper portion of settler 81 through the line 84 to fractionator 85. In the latter fractionator the hydrocarbons are distilled to produce bottoms of higher boiling point than gasoline, which may be withdrawn from the lower portion of the fractionator by the line 86, while the gasoline hydrocarbons and lighter pass overhead from the fractionator through the line 89 to a secondary fractionator or stabilizer 90 wherein a liquid fraction, comprising gasoline, is fractionated out and withdrawn from the lower portion of the fractionator through the line 91. The normally gaseous hydrocarbons, including isobutane and lighter, and a portion or all of the butane, are fractionated to separate the gases lighter than isobutane which may be removed from the upper portion of the fractionator through the valve controlled line 93. A side stream rich in isobutane may be withdrawn through the valve controlled line 94. In case there is no substantial amount of hydrocarbons lighter than isobutane, the entire fraction may be taken overhead through the line 95. The fraction removed from the line 94 or 95 as the case may be, is condensed in the

condenser 97 and collected in the accumulator 98. A portion or all of the product in accumulator 98 may be recycled through the line 9, referred to heretofore, in which is located pump 100.

In passing through the reaction zone, the isoparaffins are alkylated by the olefins in the presence of a sulfuric acid catalyst to produce branch chain paraffins comprising a mixture of about the boiling range of gasoline. The temperatures maintained in the reaction zone may be about 0 to 100° F. and preferably about 60 to 90° F. Sufficient pressure is maintained to keep the hydrocarbons substantially in the liquid phase. Best results are obtained when using an excess of isoparaffins and the molar ratio of isoparaffins to olefins may range between about 1:1 and 5:1, and preferably about 3:1. The overall of acid dosage should be between about one-half to three parts by weight of acid to one part of olefin. The acid-olefin ratio may be controlled by regulating the proportions of acid to total hydrocarbons in the fresh feed. The weight ratio of acid to total hydrocarbon or acid dosage in the individual reactors may range between about 2:1 and 5:1 and preferably above 3:1. The ratio may differ among the various reactors. The latter ratio may be regulated by the amount of acid hold-up created by recycling acid to the mixer.

In Figure 2 is shown a modified type of apparatus for carrying out a concurrent flow operation. The isoparaffin-hydrocarbon charge, introduced through the line 102 by the pump 103, and the fresh acid charge, introduced through the line 106 by the pump 107, are charged to the first of a series of mixers 108, 109, 110, 111 and 112, wherein the hydrocarbons are intimately contacted with the acid. The olefin charging stock, introduced through the line 115, in which is located pump 116, may be split into one or more of the reactors by means of the branch lines 118, 119, 120 and 121. After each mixer a settler is located, designated by the numerals 125, 126, 127, 128 and 129. The acid and hydrocarbon mixture, flowing from one mixer into the next succeeding mixer, passes through a settler wherein acid is allowed to settle out. The acid settling out in these settlers may be withdrawn in any desired amount through the lines 131, 132, 133, 134 and 135 and introduced into the lower portion of the co-operating mixer, to produce the desired amount of acid hold-up therein. It is to be understood that only a portion of the acid may be separated in the settlers either by incomplete settling or by passing only a portion of the hydrocarbon-acid mixture through the settler, the remainder going through a by-pass line, not shown. The flow of acid through the lines 131 to 135 may be by gravity or by pumps, not shown. The acid and hydrocarbon mixture from the last settler 129 is conducted to a final settler 138 wherein the acid settles out and may be withdrawn through the line 140. All or any portion of this acid may be recycled to the mixer 108 through the line 141, by the pump 142.

The hydrocarbons pass from the upper portion of the settler 138 through the line 150 to a neutralizer, not shown, to be subsequently processed, substantially as shown in Figure 1. Recycle hydrocarbons, comprising isobutane, may be recycled from the fractionating system, not shown, through the line 152 by the pump 153, which correspond to line 9 and pump 100 of Figure 1.

According to one method of operation, the acid hold-up in the various mixing sections may be maintained entirely or in part by recycling the

acid from the bottom of the final separator 138 and introducing this recycled acid into each of the mixing zones through the manifold lines 144, 145, 146, 147 and 148 by suitable regulation of the valves therein. In such an operation, the settlers 126, 128, 127, 128 and 129 may be dispensed with or by-passed, through lines not shown, and the hydrocarbon-acid mixture conducted directly to the succeeding mixer without any intervening separation or recycling of the acid.

Referring to Figure 3, there is shown a mixer 156 associated with a cooperating settler 158. The mixer and settler may comprise a stage of an alkylation unit employing either countercurrent or concurrent flow. The hydrocarbon is introduced into the mixer through line 158 and the acid through line 159. The reaction mixture is transferred through the line 160 to the settler 158 which is provided with a sight glass 162 for observing the acid level therein. The hydrocarbon settling out in the upper portion of settler 158 is withdrawn through the line 161. A plurality of draw-off lines 163, 164 and 165 connect with the settler at various elevations to control the acid level by regulation of the valves therein. The acid is allowed to flow from the settler to the mixer through the line 166 to create the desired acid hold-up which is regulated by the height of the acid level in the settler. The gas pressure in the system is equalized by means of the gas line 168 which communicates with the mixer and settler through the lines 169 and 170 respectively.

In a unit comprising a plurality of stages the acid levels may be maintained at progressively increased differential pressure between stages or any variable differential pressure may be maintained between the stages whereby any desired hold-up may be created in the various mixers, for acid hold-up purposes therein. This method is particularly suitable for a countercurrent operation.

It is contemplated that the desired amount of acid hold-up may be controlled in the individual mixers by regulating the acid levels or pressure head of acid in each of the cooperating settlers, or that the acid hold-up in the mixers may be controlled as a group by regulating the acid level or pressure head of acid in the final settler only.

As an example of the operation of the invention, isobutane and C₃ and C₄ hydrocarbons from cracking still gases, the ratio of isobutane to olefins in the over-all charge being about 3:1, were treated in a five-stage concurrent system, using multiple injection of the olefins in the second, third and fourth stages. Sulfuric acid of about 96% strength was used as the catalyst, the ratio by weight of acid to olefins in the fresh feed being about 0.6 to 1 and the ratio by weight of acid feed to total hydrocarbon feed being about 0.2 to 1. By means of settlers between the reaction stages, sulfuric acid catalyst was separated and sufficient returned to the mixing zones to maintain a ratio of acid to total hydrocarbon in the individual reactors of about 0.6 to 1 by volume or approximately 1.8 to 1 by weight. The hydrocarbons were maintained substantially in the liquid phase and the temperatures maintained at about 65° F. Used acid and excess isobutane were recycled. A yield of aviation grade gasoline, having an octane value of about 90, amounting to about 140% based on the olefins, was obtained.

Obviously many modifications and variations of the invention, as hereinbefore set forth, may be made without departing from the spirit and scope thereof, and only such limitations should be im-

posed as are indicated in the appended claims.

We claim:

1. A continuous process for the alkylation of a low-boiling isoparaffin with an olefin for the production of normally liquid hydrocarbons within the gasoline boiling range, which comprises continuously introducing in liquid phase and passing serially through a plurality of agitated reaction zones of an alkylation system maintained under alkylation conditions, a low-boiling isoparaffin and strong sulfuric acid of alkylation strength, contacting an olefin in liquid phase with the isoparaffin and acid in said zones to effect alkylation of the isoparaffin with the olefin, continuously withdrawing hydrocarbon reaction products and acid from said system, continuously discharging a minor proportion of the said acid, and continuously recycling the remaining major proportion of acid in controlled amounts to each of a plurality of said zones to provide a high acid hold-up in the system and independently maintain in each of said zones a weight ratio of acid to total hydrocarbons of about 2:1 to 5:1, the weight ratio of acid to total hydrocarbons maintained in each of said zones being substantially greater than the weight ratio of acid to total hydrocarbons in the fresh feeds to said system.

2. A continuous process for the alkylation of a low-boiling isoparaffin with an olefin for the production of normally liquid hydrocarbons within the gasoline boiling range, which comprises continuously introducing in liquid phase and passing serially through a plurality of agitated reaction zones of an alkylation system maintained under alkylation conditions, a low-boiling isoparaffin and strong sulfuric acid of alkylation strength, contacting an olefin in liquid phase with the isoparaffin and acid in said zones to effect alkylation of the isoparaffin with the olefin, continuously withdrawing hydrocarbon reaction products and acid from an intermediate zone of said system, separating the withdrawn hydrocarbon reaction products from the acid and passing the hydrocarbon reaction products to a succeeding zone of the system, recycling a portion of the separated acid to the said zone from which it was withdrawn, passing another portion of the separated acid to another alkylation zone of the system, continuously withdrawing hydrocarbon reaction products and acid from an end zone of the system and separating the same, continuously discharging a minor portion of the separated acid from the system, and continuously recycling the remaining major portion of the separated acid to the said zone, the said acid recycles providing a high acid hold-up in the system and continuously maintaining in each of said reaction zones a weight ratio of acid to total hydrocarbons of about 2:1 to 5:1, and which is substantially greater than the weight ratio of acid to total hydrocarbons in the fresh feeds to said system.

3. In a continuous process for the alkylation of a low-boiling isoparaffin with an olefin in an alkylation system for the production of normally liquid hydrocarbons within the gasoline boiling range, wherein the low-boiling isoparaffin and olefin with the isoparaffin in substantial molar excess of the olefin are simultaneously fed to an alkylation reaction zone of said system containing strong sulfuric acid of alkylation strength, the hydrocarbons in liquid phase and the acid are agitated in said zone under alkylation conditions to effect alkylation of the isoparaffin with the olefin to produce the said normally liquid hydrocarbons, reaction products are continuously re-

moved to a settling zone of said alkylation system where hydrocarbon phase is separated from acid phase, the hydrocarbon phase is treated to recover the normally liquid hydrocarbons which are discharged from the system, a portion of the acid phase is discharged from the system, and another portion of the acid phase together with fresh feed acid are supplied to said reaction zone to make up for that withdrawn with said reaction products, the improvement which comprises maintaining in said alkylation reaction zone a weight ratio of acid to total hydrocarbons within the range of about 3:1 to 5:1, and maintaining a substantial acid hold-up relative to hydrocarbons in the said alkylation system, such that the rate of flow of hydrocarbons through the system and discharging therefrom is at least twice the rate of flow of acid through the system and discharging therefrom, whereby the advantages of a low overall acid dosage with a high acid-to-hydrocarbon ratio in the reaction zone are obtained.

4. In a continuous process for the alkylation of a low-boiling isoparaffin with an olefin in an alkylation system having a plurality of alkylation stages for the production of normally liquid hydrocarbons within the gasoline boiling range, wherein the low-boiling isoparaffin and strong sulphuric acid of alkylation strength flow serially through the plurality of alkylation stages and are reacted with olefin therein under alkylation conditions, the improvement which comprises maintaining a substantial acid hold-up relative to hydrocarbons in each of a plurality of said stages, and independently controlling and varying the extent of acid hold-up maintained in at least one of said stages from the extent of acid hold-up maintained in another of said stages.

5. In a continuous process for the alkylation of a low-boiling isoparaffin with an olefin in an alkylation system having a plurality of alkylation stages for the production of normally liquid hydrocarbons within the gasoline boiling range, wherein the low-boiling isoparaffin and strong sulfuric acid of alkylation strength flow serially through the plurality of alkylation stages and the isoparaffin is reacted with olefin therein under alkylation conditions, and the resulting reaction products flow to a final settling zone where hydrocarbons are separated from the acid, the improvement which comprises returning acid from the said final settling zone in independently controlled amounts to a plurality of said alkylation stages, whereby the extent of acid hold-up in each of said alkylation stages is independently and variably controlled.

6. In a continuous process for the alkylation of a low-boiling isoparaffin with an olefin in an alkylation system for the production of normally liquid hydrocarbons within the gasoline boiling range, wherein the low-boiling isoparaffin and olefin are introduced simultaneously into an alkylation reaction zone and reacted in the presence of strong sulfuric acid of alkylation strength under alkylation conditions, and the reaction products flow to a settling zone where acid is settled from the hydrocarbons, the improvement which comprises equalizing the pressure between the said reaction and settling zones, returning acid from the settling zone to the said reaction zone in accordance with the acid level maintained in said settling zone, and controlling acid hold-up in said system by variably regulating the height of the acid level in said settling zone.

7. In a continuous process for the alkylation of a low-boiling isoparaffin with an olefin in an al-

kylation system having a plurality of alkylation stages for the production of normally liquid hydrocarbons within the gasoline boiling range, wherein the low-boiling isoparaffin and strong sulfuric acid of alkylation strength flow serially through the plurality of alkylation stages and the isoparaffin is reacted with the olefin therein under alkylation conditions, each stage of said system comprising a reaction zone and a cooperating settling zone, the improvement which comprises equalizing the pressure between a reaction zone and its cooperating settling zone of each stage, returning acid from the settling zone to the cooperating reaction zone of each stage in accordance with acid level in the settling zone thereof, controlling acid hold-up in each stage by regulating the height of the acid level in the cooperating settling zone thereof, and maintaining a different acid level in a settling zone of one stage from that maintained in another stage to thereby provide different acid hold-ups in said stages.

8. In a continuous process for the alkylation of a low-boiling isoparaffin with an olefin in the presence of strong sulfuric acid for the production of normally liquid hydrocarbons within the gasoline boiling range, wherein the isoparaffin and olefin are continuously introduced into an agitated reaction zone of an alkylation system and reacted in the presence of strong sulfuric acid under conditions to cause alkylation of isoparaffin with the olefin to produce normally liquid hydrocarbons within the gasoline boiling range, and a stream of reaction products is continuously discharged from said agitated reaction zone, the improvement which comprises passing the discharged stream to an initial settling zone, partially settling acid from the reaction products in said initial settling zone, recycling settled acid to said reaction zone, and continuously passing a stream of hydrocarbon reaction products with retained acid resulting from said partial settling operation to a final settling zone where the hydrocarbon reaction products are separated from the retained acid.

9. The process according to claim 8, wherein at least a portion of the acid separated in said final settling zone is discharged from the alkylation system, and fresh acid is added to the alkylation system to make up for that discharged therefrom.

10. In a continuous process for the alkylation of a low-boiling isoparaffin with an olefin in an alkylation system having a plurality of alkylation stages for the production of normally liquid hydrocarbons within the gasoline boiling range, wherein the isoparaffin and strong sulfuric acid of alkylation strength flow serially through a plurality of alkylation stages and the isoparaffin is reacted with olefin therein under alkylation conditions, the improvement which comprises incompletely settling acid from the hydrocarbon reaction products of one stage, passing the resultant incompletely settled hydrocarbon reaction products with retained acid to another alkylation stage of the system, and recycling separated acid to the said one stage from which it was withdrawn, whereby the acid hold-up in said one stage is dependent at least in part upon the extent of settling of acid from reaction products of that stage.

11. Process for the alkylation of hydrocarbons which comprises continuously charging an olefin, an excess of low-boiling isoparaffin and a liquid acid alkylation catalyst into a mixing zone where the hydrocarbon and acid phases are thoroughly mixed under alkylation conditions, introducing the resulting mixture into the upper portion of a

primary settling zone in which at least a partial separation of acid and hydrocarbon phases is effected, withdrawing settled acid from the lower portion of said primary settling zone and recycling it to said mixing zone, withdrawing a mixture of hydrocarbon and acid resulting from said partial settling operation from said primary settling zone, and passing said withdrawn mixture to a second settling zone where hydrocarbons separate from acid.

12. The process which comprises charging an isoparaffin and an olefin to an agitated reaction zone containing a liquid alkylation catalyst of greater density than the hydrocarbons undergoing treatment, mixing the hydrocarbons and catalyst therein under alkylation conditions to alkylate isoparaffin with the olefin, passing a stream of the resulting reaction products to a primary settling zone where incomplete settling of hydrocarbons and catalyst occurs, recycling a liquid stream from the lower portion of said primary settling zone to the reaction zone, and passing another liquid stream from a higher elevation of said primary settling zone to a second settling zone where separation of remaining catalyst from hydrocarbons occurs.

13. In the alkylation of an isoparaffin with an olefin in the presence of a liquid alkylation catalyst of greater density than the hydrocarbons undergoing treatment, the method which comprises maintaining zones of agitated reaction, partial settling and final settling in series, mixing the isoparaffin with the olefin in the presence of the liquid alkylation catalyst in the zone of agitated reaction under alkylation conditions, passing resulting reaction products to the zone of partial settling where a portion of the catalyst settles out of the reaction products, returning separated catalyst from said partial settling zone to the reaction zone, and passing partially settled reaction products from the partial settling zone to the final settling zone where remaining catalyst settles out of the hydrocarbons.

14. In a continuous process for the alkylation of a low-boiling isoparaffin with an olefin in an alkylation system having a plurality of alkylation stages for the production of normally liquid hydrocarbons within the gasoline boiling range, wherein the low-boiling isoparaffin and a liquid alkylation catalyst flow serially through the plurality of alkylation stages and are reacted with olefin therein under alkylation conditions, the improvement which comprises maintaining a substantial catalyst hold-up relative to hydrocarbons in each of a plurality of said stages, and independently controlling and varying the extent of catalyst hold-up maintained in at least one of said stages from the extent of catalyst hold-up maintained in another of said stages.

15. In a continuous process for the alkylation of a low-boiling isoparaffin with an olefin in an alkylation system having a plurality of alkylation stages for the production of normally liquid hydrocarbons within the gasoline boiling range, wherein the low-boiling isoparaffin and a liquid alkylation catalyst flow serially through the plurality of alkylation stages and the isoparaffin is reacted with olefin therein under alkylation conditions, and the resulting reaction products flow to a final settling zone where hydrocarbons are separated from the catalyst, the improvement which comprises returning catalyst from the said final settling zone in independently controlled amounts to a plurality of said alkylation stages.

whereby the extent of catalyst hold-up in each of said alkylation stages is independently and variably controlled.

16. In a continuous process for the alkylation of a low-boiling isoparaffin with an olefin in an alkylation system for the production of normally liquid hydrocarbons within the gasoline boiling range, wherein the low-boiling isoparaffin and olefin are introduced simultaneously into an alkylation reaction zone and reacted in the presence of a liquid alkylation catalyst under alkylation conditions, and the reaction products flow to a settling zone where catalyst is settled from the hydrocarbons, the improvement which comprises equalizing the pressure between the said reaction and settling zones, returning catalyst from the settling zone to the said reaction zone in accordance with the catalyst level maintained in said settling zone, and controlling catalyst hold-up in said system by variably regulating the height of the catalyst level in said settling zone.

17. In a continuous process for the alkylation

of a low-boiling isoparaffin with an olefin in an alkylation system having a plurality of alkylation stages for the production of normally liquid hydrocarbons within the gasoline boiling range, wherein the isoparaffin and a liquid alkylation catalyst flow serially through a plurality of alkylation stages and the isoparaffin is reacted with olefin therein under alkylation conditions, the improvement which comprises incompletely settling catalyst from the hydrocarbon reaction products of one stage, passing the resultant incompletely settled hydrocarbon reaction products with retained catalyst to another alkylation stage of the system, and recycling separated catalyst to the said one stage from which it was withdrawn, whereby the catalyst hold-up in said one stage is dependent at least in part upon the extent of settling of catalyst from reaction products of that stage.
